GAME BOARD

Reginald V. Bovill, Dearborn, Mich.

Application May 31, 1955, Serial No. 36,281

Term of patent 3½ years

(Cl. D34—5)

The single figure is a top plan view of a game board, embodying my new design. The back thereof is plain or conventional.

The game board is of conventional thickness.

The essential features of my design reside in the portions shown in solid lines on the drawing.

I claim:

The ornamental design for a game board, as shown and described.
